UNITED STATES PATENT OFFICE.

GEORGE ELMER GORHAM, OF ALBANY, NEW YORK.

INVALID-BEDSTEAD.

SPECIFICATION forming part of Letters Patent No. 559,974, dated May 12, 1896.

Application filed June 21, 1895. Serial No. 553,503. (No model.)

To all whom it may concern:

Be it known that I, GEORGE ELMER GORHAM, a citizen of the United States, residing at Albany, in the county of Albany and State of New York, have invented certain new and useful Improvements in Invalid-Bedsteads; and I do hereby declare the following to be a full, clear, and exact description of the invention, such as will enable others skilled in the art to which it appertains to make and use the same.

In Letters Patent of the United States granted to me September 11, 1894, No. 525,952, I have described an invalid-bedstead wherein the bed-bottom may be tilted longitudinally for the purpose of facilitating the insertion of a bed-pan beneath the invalid and for bringing him into a sitting position thereon and for the purpose of facilitating the insertion of the canvas strips of a stretcher-frame beneath him and elevating him above the mattress thereby with ease and celerity.

My present invention relates to certain improvements in the bedstead referred to and its accessories, as hereinafter described, and particularly pointed out in the claims.

In the accompanying drawings, Figure 1 represents in perspective a bedstead embodying my improvements tilted forwardly and with the bed-pan, seat-support, and table-rest in position. Fig. 2 represents in full lines a bottom plan view of the seat proper and shows in dotted lines the operation of the seat-sustaining legs. Figs. 2^a and 2^b represent in detail the castings for said seat. Fig. 3 represents the bedstead in side elevation, and illustrates the manner of raising the stretcher-frame so as to lift the invalid from the mattress while the bedclothes are being renewed. Fig. 4 represents an attachment for exerting a uniform extending strain upon the broken leg of a patient. Fig. 5 represents a side elevation, partly in section, of the bedstead in a horizontal position and with an india-rubber tank in place for bathing the patient or for raising or lowering his temperature. Fig. 5^a represents a view of the shoring-piece used in elevating the stretcher-frame. Fig. 6 represents a section on the line 6 6 of Fig. 5, omitting the tank. Fig. 7

represents a detail view of one of the actuating-arms for the tilting bed-bottom, and shows the manner of connecting said arm thereto. Fig. 8 represents in side elevation the bedstead as applied to the restraint of an invalid in delirium. Fig. 9 represents a longitudinal sectional view of the bedstead, showing the invalid in a substantially sitting position. Figs. 10, 11, and 12 represent detail views showing the manner in which the end posts and side bars of the bedstead are assembled. Figs. 13 and 14 represent detail views of the manner of jointing the legs of the supporting-standard of the bedstead and of sustaining the side bars therefrom. Figs. 15 and 16 represent detail views of the joint between a side bar of the bedstead and the corresponding arm of the table-rest support, and Figs. 17 and 18 represent detail views of the adjusting-rack for the table-rest leg.

Similar letters of reference indicate similar parts throughout the several views.

Referring to the drawings, it will be noted that the bed-bottom is provided with brackets *c*, having forked ends *c'*, within which rest the side bars *d* and wherein they are removably secured by bolts and nuts, as shown in detail in Figs. 13 and 14. The brackets *c* are mounted to turn freely upon the cross-bar *b*, having screw-threaded ends provided with nuts *b'* to prevent the brackets from slipping off the said bar. The cross-bar *b* also serves as the connection for the legs *a* of the supporting-stand of the bed-bottom, the contiguous ends of the said legs being provided with lugs *a'*, free to turn upon the cross-bar *b* when it is desired to fold the stand for storage or shipment. When the stand is set up for use, the legs *a* are held securely at the desired angle of spread by the rods *h'*, having hooked ends which snap over rods *h*², which connect each pair of legs. For convenience the legs *a* are preferably provided with the usual casters, as shown.

The bed-bottom frame is so constructed that the head and foot sections may be readily removed for storage or transport, or so as to convert the bed, when desired, into an operating-table, freely accessible from all points. To this end the side bars *d* (which are pref-

erably of gas-pipe) are received at each of their extremities within a socket formed in a suitable casting f , as indicated in detail in Figs. 10, 11, and 12. The casting is provided with a conical lug d^3 , terminating below in screw-threaded pin d^4 , sweated or otherwise secured therein. A coöperating socketed casting e is provided for each of the uprights d^2 of the head and foot boards, and this casting has a conical mortise adapted to receive and interlock with the conical lug d^3 , thereby assembling the two castings, whereupon they may be removably secured together by means of the nut d^5 and washer d^6 . In this manner the head and foot boards are securely united to the side bars of the bed, but may be quickly removed by unscrewing the nuts d^5 . The castings f are provided with upwardly-extending lugs f' , serving as means of attachment for the connecting angle-irons f^2 , to which the selvage edges of the woven-wire fabric m^3 are fastened. Upon this stretched woven-wire fabric is adapted to rest any suitable form of bed-mattress m^4 .

The bed-bottom as thus constructed is adapted to be tilted when desired, for the purposes set forth in my Letters Patent hereinbefore referred to. To opposite legs of the stand are secured short uprights d^7 , within which is journaled to turn freely the right and left hand screw-shaft g^8 , provided at its end with the operating-wheel f^3 . With the threads of the screw-shaft engage the nuts f^4 , adapted to travel from or toward each other according as the wheel is turned in the one direction or the other. As indicated in detail in Fig. 7, each nut is provided with side lugs serving as journal-bearings for the fork f^5 of a swinging link f^6 . The upper end f^7 of the link is made spherical and is adapted to engage within a socket-bearing f^8 , made up of two parts. (Shown separated in Fig. 7.) This bearing is provided with lugs whereby it may be rigidly secured to the side bar d by bolts and nuts f^9 passing through the said lugs and side bar.

The bed-bottom is thus connected to the shaft g^8 through the intermediacy of swinging links having a ball-and-socket joint at one end, which permits universal motion thereat, and having at its other end a joint having at all times a movement in a plane normal to the shaft. The gearing remains set at whatever position of tilting the bed-bottom may be left by the operator, and the great leverage afforded enables it to be operated with ease and certainty in either direction. When the bed-bottom is in the horizontal position, I relieve the strain upon the gearing by means of the rest s^{10} , consisting, preferably, of an iron rod of general U shape adapted to swing into the sustaining vertical position shown in Fig. 5.

Pivoted to each of the side bars d (by means of a bolt x and coöperating nut and washer, as shown in Figs. 15 and 16) is a rod p , to which

is jointed a second rod p' , having a pointed end p^2 , adapted to engage with any one of a series of holes formed in a plate p^3 , secured to the inner side of d . These jointed rods constitute brackets for the table p^4 , as shown in Figs. 1 and 9. When the table is not in use, the jointed rods fold together out of the way, as shown in Figs. 3 and 5. The adjustability of the bracket through the intermediacy of the series of holes referred to enables the table to be placed in a horizontal plane to whatever degree the bed may be forwardly tilted.

The seat and foot rest for enabling the invalid to remain comfortably in an inclined or sitting position is of great simplicity and effectiveness for the particular use intended. It consists of two side straps p^7 , adapted to be secured by loop and buckle to the head-board uprights d^2 and adapted to be secured at their opposite ends to the padded seat-board p^{10} by means of end caps. (Shown in detail in Fig. 2.) From said end caps straps p^8 extend to the padded foot-board p^9 . Each end cap is provided with a socket-recess v , into which the end of the seat-rest extends and wherein it is secured by screws passing through the holes v' . The aperture v^2 serves as the means of connection of the strap p^7 and the aperture v^3 as the means of connection of the strap p^8 . The surface v^4 of the end cap is made smooth, and a rivet v^5 passes through said surface and serves as a pivot upon which is adapted to turn the swinging leg v^6 , connected to the casting by said rivet.

When the seat is in use simply as a support for sustaining the invalid in the sitting posture, it is arranged as in Fig. 9, which illustrates its mode of use on such occasions. The foot-rest serves as a support for the feet, or for one foot if the other leg is broken, as indicated in said Fig. 9. The flexibility of the straps p^8 permits the foot-rest to be moved to one side of the broken leg, so as to support the uninjured leg without interfering with the broken one. Both the seat-rest and foot-rest are adjustable jointly and independently by means of their adjustable straps.

When the invalid desires to evacuate, the swinging legs v^6 are brought into the position shown in dotted lines in Fig. 2 and in full lines in Fig. 1, thereby leaving a free and unobstructed place beneath the seat-rest. The bed-pan z is thereupon inserted within this space, as indicated in Fig. 1, and pressed forward against and beneath the hips into appropriate position, which position it thereupon retains without further expedient and with complete security against soiling the bed-clothes. This is due to the combined action of the inclined bed-surface and the bed-pan of the peculiar construction illustrated. The main characteristic of the latter is that its forward edge is flush with its sides, whose top edges form such an angle with the bed-pan bottom as to come into a substantially horizontal position when the bed is tilted forward.

- I thus dispense entirely with the forwardly-extending projection which is the usual adjunct of bed-pans of this general character, and which is not only a source of discomfort to the invalid, but is itself an element of unreliability in the cleanly use of the pan. In practice I prefer to construct my pan from sheet metal and to provide it with a handle for ready manipulation.
- 10 The device shown in Fig. 9 for applying extension to a broken leg, and which constitutes one of the adjuncts of the tilting bed, is illustrated in detail in Fig. 4. It consists of a yoke *w*, connected to vertical bars *w'* of the foot-board and sustaining the bearings of a sheave *w²*. Over this sheave passes a stout cord or small flexible rope *w³*, having the adjustable weights *w⁴* and connected at its forward end to the customary cross-piece *w⁵*, whose side pieces *w⁶* are firmly secured to the patient's broken leg. By varying the number or size of the weights the desired tension may be applied to the leg. The entire flexibility of the cord *w³* in the general combination enables 25 the tension device to maintain its useful function and to operate with substantial uniformity at all positions of tilting of the bed-bottom.
- As in my former patent referred to, so also 30 in the present case I make use of a stretcher-frame for the purpose of raising the invalid from the mattress, when occasion requires, and suspending him from the bed-frame. The operation of thus raising the invalid is 35 in substance the same as described in the former patent, and the several steps thereof are indicated herein in Fig. 3. The stretcher-frame consists of the tubular side bars *l* and the end yokes *l' l''*, fitting within said bars 40 and removable thereof. Canvas strips *l³* are adapted to be inserted beneath the invalid to form the stretcher-bottom. To raise the invalid clear of the bed-bottom, the attendant is provided with the shoring-piece *s²*, (shown 45 in Fig. 5^a,) consisting of an iron rod bent at its middle and having diverging legs, provided on one side with hook projections *s³* and on the other side with additional hook 50 projections *s⁴*. While the bed-bottom is in the horizontal position the attendant places the hooks *s³* of the shoring-piece beneath the yoke *l'* and sets the shoring-piece in a slightly-inclined or bracing position, as shown in Fig. 9. He then operates the hand-wheel 55 so as to cause the bed-bottom to tilt toward the shoring-piece. During this first tilting operation the end of the stretcher-frame supported by the shoring-piece remains stationary, and when the bed-bottom is so far tilted 60 that the yoke *l'* is higher than the hooks or catches *s⁵* on the uprights a bar *s⁶* is placed upon *s⁴*. The bed-bottom is then tilted in the reverse direction until the yoke *l'* rests upon the bar *s⁶*, and the shoring-piece is then 65 transferred to the other end of the bed and its hooks *s⁴* are placed beneath the yoke *l''*, and the tilting is continued until the bed-bottom is tilted slightly beyond its original horizontal position. The yoke *l''* is then above the hooks or catches *s⁷* of the head-section 70 uprights, and a bar *s⁸* is placed upon said catches *s⁷*. Thereupon a slight tilting forward releases the shoring-piece, deposits the yoke *l''* upon the bar *s⁸*, and brings the bed-bottom into the horizontal position with the 75 stretcher supported above it, all as indicated in Fig. 3. A reversal of these operations suffices to restore the invalid to the mattress, as will be readily understood. The bars *s⁶* and *s⁸* are hooked at their ends, so as to prevent 80 them from sliding off endwise from the catches, and are preferably provided with short sleeves of soft india-rubber or the like, as indicated in Fig. 6, so as to afford an additional safeguard against slipping. Collars *s⁹* 85 upon the yokes *l' l''* rest upon these sleeves to prevent any tendency of the stretcher-frame to move longitudinally during the tilting operation.
- As illustrated in Fig. 5, the stretcher-frame 90 may be employed as a means of suspension for the sides of an india-rubber bath-tub *x'* when it is desired either to bathe the invalid or to lower his temperature by the application of ice or cold water, as in the modern 95 treatment of typhoid fever and the like. Thus, after elevating the invalid upon the stretcher, as hereinbefore described, the bath-tub could be set in place. The invalid could then be lowered upon the bottom of the bath- 100 tub and the canvas strips removed. The stretcher-frame is thereupon again raised and suspended in the position shown in Fig. 5, and the sides and ends of the tub are attached by hooks *x'* to the side bars of the 105 stretcher-frame and to the bars *s⁶ s⁸*. The bath-tub is provided with tube *x²*, having a stop-cock *x³*, for the purpose of drawing off the water when it is no longer needed, whereupon the flexible tub can be readily removed, 110 either by raising the invalid on the stretcher-frame, as before, or by sliding it from under him if his condition will permit it.
- In Fig. 8 I have illustrated the application of my stretcher-frame to effect the restraint 115 of delirious invalids. The patient, in this instance, is placed beneath the canvas strips of the stretcher-frame in such manner as to pinion his arms and legs, and the stretcher-frame is then securely strapped to the bed-bottom 120 by broad strips of canvas *x³*, joining the side bars *d* and *l*.
- Having thus described my invention, what 125 I claim is—
1. In an invalid-bedstead, the combination of a stand, a tiltable bed-bottom mounted thereon, a power-shaft on the stand having a right and left screw-thread, traveling nuts upon the screw-threaded power-shaft, arms jointed at their lower end to the nuts and 130 provided at their opposite ends with globular projections, and sockets, connected to the

bed-bottom, receiving said globular projections; substantially as described.

2. In an invalid-bedstead, the combination of a stand, a tilttable bed-bottom mounted thereon, a power-shaft on the stand having a right and left screw-thread, traveling nuts upon the screw-threaded power-shaft, arms provided at their lower end with yokes journaled to opposite sides of the nuts, said arms being provided at their opposite ends with globular projections, and sockets, connected to the bed-bottom, receiving said globular projections; substantially as described.

3. In an invalid-bedstead, the combination of a stand, a tilttable bed-bottom mounted thereon, a power-shaft on the stand having a right and left screw-thread, traveling nuts upon the screw-threaded power-shaft, arms jointed at their lower end to the nuts and provided at their opposite ends with globular projections, and sockets, connected to the bed-bottom, receiving said globular projections, said sockets being made up of separable halves having extensions for bolting them to the side bars of the bed-bottom; substantially as described.

4. In an invalid-bedstead, the combination of a stand, a tilttable bed-bottom mounted thereon, a power-shaft on the stand having a right-and-left screw, traveling nuts upon the screw-threaded power-shaft, said nuts having bosses on their opposite sides, arms provided at their lower end with yokes having bosses and connected to the nut-bosses by journal-pins, and a universal-joint connection between the upper ends of the arms and the bed-bottom; substantially as described.

5. In an invalid-bedstead, the combination with the tilttable bed-bottom and the stand upon which the bed-bottom is supported, of brackets pivoted to the stand and provided with saddles or yokes within which the side bars of the bed-bottom rest, and means for connecting said yokes to the side bars; substantially as described.

6. In an invalid-bedstead, a seat-rest provided with means for sustaining it from the upper part of the bed; substantially as described.

7. In an invalid-bedstead, a seat-rest provided with means for sustaining it from the upper part of the bed, said means consisting of flexible straps; substantially as described.

8. In an invalid-bedstead, a seat-rest provided with means for sustaining it from the upper part of the bed, and a foot-rest supported from the seat-rest; substantially as described.

9. In an invalid-bedstead, a seat-rest provided with means for sustaining it from the upper part of the bed, and a foot-rest supported from the seat-rest by flexible straps; substantially as described.

10. In an invalid-bedstead, a seat-rest adapted to rest upon the surface of the bed

and means for raising and supporting said seat-rest at its ends above the surface of the bed; substantially as described.

11. In an invalid-bedstead, a seat-rest adapted to rest upon the surface of the bed, and means for raising and supporting said seat-rest at its ends above the surface of the bed, said means consisting of bracket-legs connected to the ends of the seat-rest; substantially as described.

12. In an invalid-bedstead, a seat-rest adapted to rest upon the surface of the bed, and means for raising and supporting said seat-rest at its ends above the surface of the bed, said means consisting of bracket-legs connected to the ends of the seat-rest, and hinged to fold longitudinally thereof; substantially as described.

13. In an invalid-bedstead, a seat-rest provided at its ends with socket-pieces, and bracket-legs pivoted to said socket-pieces, and adapted to fold longitudinally of the seat-rest; substantially as described.

14. In an invalid-bedstead, a seat-rest provided at its ends with socket-pieces, and bracket-legs pivoted to said socket-pieces and adapted to fold longitudinally of the seat-rest, and flexible straps connected to the socket-pieces and extending to the upper portion of the bedstead; substantially as described.

15. In an invalid-bedstead, a seat-rest provided at its ends with socket-pieces, and bracket-legs pivoted to said socket-pieces and adapted to fold longitudinally of the seat-rest, and flexible straps connected to the socket-pieces and extending to the upper portion of the bedstead, in combination with a foot-rest and flexible straps connecting said foot-rest with said socket-pieces; substantially as described.

16. In an invalid-bedstead, the combination with the end boards having retaining catches or hooks thereon, of a stretcher-frame, and removable sustaining-rods for said stretcher-frame adapted to rest upon said hooks or catches; substantially as described.

17. In an invalid-bedstead, the combination with the end boards having retaining catches or hooks thereon, of a stretcher-frame, and releasable sustaining-rods for said stretcher-frame adapted to rest upon said hooks or catches, and provided at their ends with sleeves of soft india-rubber; substantially as described.

18. In an invalid-bedstead, the combination with a stretcher-frame provided with cross-strips of canvas connecting the side bars of said stretcher-frame, of adjustable connections between the side bars of the stretcher-frame and the side bars of the bed-bottom, whereby the patient may be held in restraint between the canvas strips and the body of the bed; substantially as described.

19. In an invalid-bedstead, the combination with the bed-bottom of a supplemental

frame, means for supporting said frame above the bed, and a flexible bath-tub supported at its edges from the frame; substantially as described.

5 20. In an invalid-bedstead, the combination with the bed-bottom of a supplemental frame, means for supporting said frame above the bed, and a flexible bath-tub supported at

its edges from the frame and provided with an outflow-pipe; substantially as described. 10

In testimony whereof I affix my signature in presence of two witnesses.

GEORGE ELMER GORHAM.
